ISRAEL FOSTER, OF PHILADELPHIA, PENNSYLVANIA.

Design No. 3,305, dated January 5, 1869.

DESIGN FOR A CARPET-PATTERN.

The Schedule referred to in these Letters Patent and making part of the same

To all whom it may concern:

Be it known that I, ISRAEL FOSTER, of Philadelphia, county of Philadelphia, State of Pennsylvania, have originated a new Design for a Pattern to be inwrought into Carpets or other fabrics; and I do hereby declare that the accompanying drawing, and following explanation thereof, form a full, clear, and exact description of the said design.

In the drawing, the figure represents sufficient of a carpet or other fabric to illustrate the design.

The body or ground-work of the fabric is made up of stripes *a* and *b* of different shades, and of varying widths.

A A represent portions (equivalent to one-quarter) of the principal member of the pattern, the remaining three-quarters of the member being merely a repetition of that which is shown.

This member *A* consists of a square or diamond-shaped figure, formed of the bars *c*, which figure is intersected by bars *d* and *d'*, crossing each other at right angles.

The member *A* is surrounded by ornamental figures, composed of stems, leaves, and flowers, and the internal ornamentation of the bars *c*, *d*, and *d'*, is too clearly shown in the drawing to need description.

B *B* are small figures, of a form similar to that of the members *A*, and arranged, with respect to the latter, as illustrated.

The figures *B* are connected by a diagonal, vine-like ornament, *f*, which, in its general direction, is parallel with the bars *c* of the principal members *A*.

Irrespective of the colors employed,

I claim the design for the pattern of a carpet or other fabric, substantially as represented in and by the accompanying drawing.

In testimony whereof, I have signed my name to this specification, in the presence of two subscribing witnesses.

ISRAEL FOSTER.
